United States Patent Office

Des. 232,148
Patented July 23, 1974

232,148

ELECTRIC CASSEROLE OR SIMILAR ARTICLE

Harold E. Yarrington, Eau Claire, Wis., assignor to
National Presto Industries, Inc., Eau Claire, Wis.

Filed Aug. 31, 1972, Ser. No. 285,367

Term of patent 14 years

Int. Cl. D7—02

U.S. Cl. D7—94

Fig. 1

Fig. 2

Fig. 3

Fig. 4

FIG. 1 is a top and front perspective view of an electric casserole or similar article showing my new design; FIG. 2 is a top plan view thereof;

FIG. 3 is a side elevational view thereof, the opposite side being a mirror image thereof; and

FIG. 4 is a rear elevational view thereof.

The conventional electric element is visible on the bottom of the electric casserole in FIGS. 3 and 4.

I claim:

The ornamental design for an electric casserole or similar article, substantially as shown and described.
